Application August 7, 1944, Serial No. 548,383

1 Claim. (Cl. 100—70)

1

This invention relates to improvements in pneumatic presses and has as its general object to provide a press of relatively simple and inexpensive construction which is capable of delivering a rapid succession of strokes having extreme accuracy of stroke limit. A further object of the invention is to provide a press which eliminates the wear and tear upon the clutch used in the conventional flywheel and crank-type press. A further object is to provide a press adapted to deliver a stroke of maximum terminal power with a minimum expenditure of energy in the over-all operation of the press. A further object is to provide a press which permits of rapid variation in the speed of operation thereof without wasting power and without straining the mechanism.

The invention contemplates a pneumatically powered, toggle stroke delivery mechanism type of press and aims particularly to provide a press of this type which is capable of delivering twice as many working strokes per cycle of motor operation, and which provides for greater accuracy of stroke and correspondingly more uniform accuracy in the workpiece, than has been possible in prior presses of this general type. To this end, the invention provides for through-center operation of the toggle mechanism by the pneumatic servo motor, so that the working stroke of the ram terminates in the middle rather than at the end of a movement of the servo motor. This arrangement produces the double advantage of improving the accuracy and uniformity of the length of the ram stroke and also doubles the number of ram strokes per cycle of servo motor operation.

A further object of the invention is to provide a novel and improved control mechanism for a double acting servo motor, wherein automatic control is derived from the device actuated by the servo motor.

Another object is to provide a press which may be converted from single stroke to continuous operation simply by turning a valve handle.

Another object of the invention is to provide a pneumatically-powered press which can readily be synchronized with a cooperating machine such as, for example, an automatic feeding device.

Like reference characters designate similar parts in the several views of the drawings, in which:

Fig. 1 is a front elevation of the press;

Fig. 2 is a section taken on the line 2—2 of Fig. 1;

2

Fig. 3 illustrates diagrammatically the operating circuit;

Fig. 4 is a detail of the valve arrangement taken on line 4—4 of Figs. 1 and 5; and

Fig. 5 is a side elevation partially in section of the valve shown in Fig. 4.

As an example of one form in which the invention may be embodied, I have shown in the drawings a light punch press comprising a frame 1 having parallel side members provided with slide ways 3—3' in which is mounted, for vertical reciprocation, a ram 2. Movement is transmitted to the ram 2 by toggle mechanism comprising pairs of toggle arms 4—4' and 5—5' pivotally joined together by a shaft 8 and pivoted respectively at their remote ends to the ram 2 by trunnions 1—1' and to the frame 1 by a shaft 6. The shaft 6 is secured to the arms 4 and journaled in the frame 1. A tool 7a may be supported in the ram 2 and adapted to cooperate with a suitable mating tool mounted on the bed 7b of the press.

Vertical reciprocating movement of the ram 2 is produced by alternately moving the pivotal joint between the toggle arms first to one side and then to the other side of the axis of ram movement, and for this purpose I provide a pneumatic servo motor comprising a cylinder 11 pivoted at 12 to the frame and having a double acting piston 31 (Fig. 3) to which is fixed a piston rod 10 linked to the shaft 8 by a cross head 9. It may be noted at this point that the stroke of the tool 7a is delivered when the piston 31 is intermediate the ends of its stroke. In the single stroke type of operation that has previously characterized toggle presses of this type, it has been impossible to terminate the piston stroke with sufficient accuracy at the exact point of on-center alignment of the toggle arms so as to attain uniformity of ram stroke. By moving the toggle through center and delivering the ram stroke while the piston is in full motion, I provide much greater accuracy and striking power in the ram stroke and at the same time provide for double the number of ram strokes per cycle of servo motor operation.

Retracting movement of the piston 31 is effected by introducing air through a feed line 29 into the chamber 30 formed between the one side of the piston 31 and the cylinder 11. Extending movement of the piston 31 is effected by introducing air under pressure through a line 33 into the chamber 32 defined between the opposite side of the piston 31 and the cylinder 11. When air is being introduced through the line 29 into the

chamber 30, air from the chamber 32 is exhausted through the feed line 33, and vice versa.

For reversing the flow through the lines 29 and 33, I provide a slide valve including a casing 25 having ports 28 and 34 with which the lines 29 and 33 communicate, having an inlet 26 communicating with a source of air under pressure, and having discharge vents 36 and 42 respectively, the former adapted to vent air from the line 33 while the inlet 26 is delivering air to the other line 29 and the latter adapted to vent air from the line 29 when the inlet 26 is delivering air to the line 33. Slidably mounted in a bore 50 in the casing 25 is a valve plunger 38 having spaced valve ports 27 and 35 respectively (each enlarged at the surface of the plunger so as to bridge the space between the inlet 26 and the ports 28, 34 respectively) the port 27 being adapted at one limit of plunger movement to establish communication between the inlet 26 and the line 29 while the port 35 establishes communication between the line 33 and the vent 36, and the port 35 being adapted at the other limit of plunger movement to establish communication between the inlet 26 and the line 33 while the port 27 establishes communication between the line 29 and the vent 42.

On the respective ends of the plunger 38 are pistons 37 and 39 which operate respectively in cylinders 45 and 43 formed in the respective ends of the casing 25. For moving the slide valve toward the right as viewed in the drawings, air is introduced from a line 22 into the cylinder 43 to act against the piston 39 while air behind the piston 39 is bled through a vent 44. Simultaneously, air in the cylinder 45 is vented through the line 21 in response to movement of the piston 37, and air enters the cylinder 45 through a vent 41 to fill the space behind the piston 37. In the movement of the plunger in the opposite direction, the flow is reversed.

The flow through the lines 21 and 22 is controlled by a pilot valve comprising a cylindrical casing 15 mounted on the frame 1 and encircling one end of the shaft 6 which is oscillated by the upper toggle arms 4. The air lines 21 and 22 connect respectively with ports 19 and 20 circumferentially spaced in the casing 15. The shaft 6 has a central bore 16 which is connected to a source of air under pressure by a fitting 17 threaded into the end of the shaft 6, a rotatable coupling 17a, and a feed line 17b. A passage 18 in the shaft 6 delivers air from the bore 16 to the port 19 when the arms 4 are at one limit of their movement and to the port 20 when the arms 4 are at the other limit of their movement. When the passage 18 is thus delivering air to the line 21, the line 22 is vented through a vent 18b in the periphery of the shaft 6, registering with the port 20 and opening into the end of the shaft 6. When the passage 18 is delivering air to the line 22, the line 21 is vented through a vent 18a, similar to the vent 18b but located in the shaft 6 on the opposite side of the passage 18 as shown.

The pilot valve operates to shift the plunger 38 from one limit of its movement to the other limit thereof prior to any substantial movement of the servo motor piston 31. With the slide valve thus shifted, the pilot valve has completed

its function until the next half cycle of operation of the servo motor has taken place, and the slide valve continues to function until that half cycle of operation is completed, the pilot valve being then shifted for the next half cycle of operation.

The invention lends itself readily to synchronization with a cooperating machine without change in the above-described mechanism. All that is necessary in order to achieve such synchronization is to control the pilot valve feed line 17b from the cooperating machine. For example, where it is desired to synchronize the press with a feeding device such as that shown in Fig. 3, including a slide 47 operated by any suitable source of reciprocating movement (such as the crank shaft 48 driven by a motor 49 and connected to the slide 47 by a pitman 56) it is only necessary to provide a control valve operated by the slide 47 when the latter has completed its cycle of operation, and for the purpose of illustrating such a valve, I have shown a valve including a casing 51 having an oscillatory valve element 52 therein operated by an arm 53 which in turn is moved in one direction by the slide 47 and in the other direction by a spring 54. By connecting the line 17b and a feed line 55 in properly spaced relationship to the casing 51, the valve may be made to cut off the flow of air under pressure to the pilot valve except for a short interval at the limit of retracting movement of the slide 47, during which interval the air may be supplied to the pilot valve for a sufficient length of time to reverse the slide valve. While I have shown a power-driven source of movement for the slide 47 it is to be understood that the slide 47 could, if desired, be operated manually and the press would automatically operate in response to the manual operation of the slide. It is also to be understood that while the movement of the cooperating machine has been described, for illustrative purposes, as a reciprocating movement, that it need not necessarily be that type of movement but could be any other type, such as, for example, rotary movement.

The foregoing may be taken as illustrative of one form in which the invention may be embodied, it being my intention to cover in my claim the use of any equivalent arrangement or apparatus.

I claim as my invention:

In a press, a frame, a ram adapted to have linear reciprocating movement with reference to said frame, a toggle comprising a pair of arms pivotally joined to each other, the remote ends of one of said arms being attached to a trunnion member which is journaled in said frame, the remote end of the other arm being pivoted to said ram, a double acting pneumatic servo motor linked to the pivotal joint between said arms, air circulating means for delivering air under pressure to one end of said servo motor while exhausting air from the opposite end thereof, and means for reversing the flow in said circulating means at predetermined limits of reciprocating movement of said servo motor, comprising a valve having an oscillating valve element comprising an extension of said trunnion and receiving movement therefrom.

LUTHER F. DAY.
